BELLOWS FOLDING MACHINE

Archie McMillan, Bernie Beeker, and Arthur C. Mickey, Saginaw, Mich., assignors to General Motors Corporation, Detroit, Mich., a corporation of Delaware

Application January 24, 1950, Serial No. 140,302

20 Claims. (Cl. 93—77)

1

This invention relates to folding machinery and more particularly to a continuous bellows folding machine.

The bellows forming machine folds a continuous paper strip into a tube and then forms pleats in the tube. The paper or other suitable sheet filtering material is fed in a continuous strip into the machine between the internal and external tube formers. The internal tube former is a generally cylindrical member supported from the top by a bridge located at the entrance side of the machine. The external former is mounted concentrically around the internal former. The external former is shaped to provide a wide flat scoop-like portion disposed below the entrance end of the internal former, and a generally tapering intermediate section terminating in a cylindrical portion closely surrounding an intermediate portion of the internal former. Two groups of power driven rolls then engage the paper tube and draw it along the internal former. One of these rolls is heated to seal the joint in the paper tube. The terminal end of the internal former gradually tapers from a circular cross section to a square cross section and has a reduced portion connected to an extension having a small square section. The pleat folding portion of the machine surrounds this square extension. The pleat formers consist of four series of formers mounted on endless chains. Air pressure is supplied through the internal tube former to apertures in the reduced or neck portion to hold the blank in contact with the pleat formers. The top and bottom series of formers grip the flat top and bottom portions of the square blank over the neck part of the former to fold opposed pleats. The series of formers on each side grip the flat side portions over the neck portion of the former to fold opposed pleats intermediate the opposed top and bottom pleats. The formers then move both longitudinally and radially to release the completed bellows while a mandrel extension holds the completed bellows centrally located between the formers.

A primary object of the invention is to provide a continuous folding machine employing air pressure to assist in the folding of the sheet material in cooperation with mechanical folding devices simultaneously operating on the sheet material.

Another object of the invention is to provide in a continuous bellows folding machine an internal mandrel and external tube forming guide, a reduced portion in said mandrel where the tube is supported by air pressure while the tube is

2

formed into a series of pleats as it is continuously passed through the machine.

Another object of the invention is to provide in a continuous folding machine a mandrel having a reduced portion with air pressure connections to support the tube over the reduced portion and external members to fold the tube in cooperation with the internal air pressure.

Another object of the invention is to provide in a continuous folding machine a plurality of folding elements moving in a continuous path so that they engage the blank and form the folds and they move longitudinally with the blank as it moves through the machine and simultaneously withdraw from the folds.

These and other objects of the invention will be more fully explained in the following drawings and specification which provide a complete description of a preferred embodiment of the invention.

Figure 1 is a partial side view of the folding machine.

Figure 2 is a partial perspective view of the blank showing the successive steps of forming a bellows.

Figure 3 is a partial elevation view of the folding machine.

Figure 4 is a view on the line 4—4 of Figure 1.

Figure 5 is a view on the line 5—5 of Figure 4.

Figure 6 is a partial section on the line 6—6 of Figure 1.

Figure 7 is a partial section on the line 7—7 of Figure 1.

Figure 8 is a section on the line 8—8 of Figure 1 with parts broken away and in section.

Figure 9 is a side view of the pleat forming portion of the machine.

Figure 10 is a partial cross sectional view of the pleat former drive gearing on the line 10—10 of Figure 11.

Figure 11 is a partial cross section of the pleat formers on the line 11—11 of Figures 1 and 9.

Figure 12 is a sectional view of the pleat formers showing the mandrel.

The folding machine is mounted on a table 10 which is supported by suitable legs 12 as shown in Figures 1 and 2. At the entrance end of the machine a pair of posts 16 and 17 are mounted at each side of the table 10 to provide support for guiding and gluing mechanism. As the endless strip of sheet material enters the machine it engages the roller 18 which is supported by a pair of brackets 20 which are shown in detail in Figure 5. The brackets 20 also provide support for a platen 22 and an upper guide 24 and side

guides 26. The post 16 on the right looking toward the entrance of the machine as in section 4 supports a glue nozzle 28 by means of a cross-head 30. The crosshead 30 is slidably mounted on the vertical slideable head 32. A suitable tongue and groove connection 34 between the vertical slide 32 and the crosshead 30 allows horizontal sliding movement of the crosshead 30 relative to the sliding head 32 to transversely adjust the nozzle 28. An adjusting screw 36 is rotatably mounted on and axially restrained by the bracket 38 secured to the crosshead 30 and threadably secured in a bore in the slide member 32. The slide member 32 is slidably mounted on a block 40 secured to the post 16 by a similar tongue and groove connection 42. Another adjusting screw 44 is rotatably mounted in a bracket 46 secured to the block 40 and threaded into a bore in the slide member 32 in order to vertically adjust the slide member. Immediately above the nozzle 28 a flexible platen extension 48 is attached to the upper guide 24 to support the paper at the point where the adhesive impinges on the paper.

The other nozzle 52 is located on the upper side of the paper and supported from the left post 17 by a similar crosshead 30. As described above in conjunction with nozzle 28, the crosshead 30 is slidably mounted by a tongue and groove connection 34 on a slide member 32. The slide member is similarly connected by a tongue and groove connection 42 to a supported block 40 which is attached to the left post 17. Similar adjusting screws 36 and 44 control the horizontal and vertical position of the nozzle. A platen extension 54 is supported by platen 22 immediately below the nozzle 52 in order to support the paper at the point where the adhesive impinges on the paper.

The upper guide 24 has an axial extension 56 extending above the paper to the entrance portion 58 of the external former 60. The entrance portion 58 on the external former is flat and is supported by posts 63 on table 10. The external former 60 extends forward and gradually changes from the flat section at the entrance edge 58 as shown in Figure 1 to a substantially cylindrical shape with an opening at the top as shown in Figure 6. At this point the entrance edge of the internal cylindrical former or a mandrel 62 is positioned within the external former. The mandrel 62 is supported by a hanger 64 depending from the bridge plate 66 supported between the bridge arches 72 and 74. The rear bridge arch 74 may be braced by a diagonal strut 76. A compressed air pressure supply passage 78 conducts air pressure to the hollow interior of mandrel 62. The external former 60 extends forward through the support or bridge arches 72 and 74 and gradually approaches a circle cross section and terminates at about the center of the mandrel 62 in a substantially cylindrical terminal portion 82 which is spaced from the mandrel 62 a distance substantially equal to the thickness of the sheet material or paper being folded in the machine. The terminal portion 82 of the outer former 60 has a reinforcing ring 84 which is secured to the supported post 86. A folding guide 88 is adjustably mounted on the top portion of the reinforcing ring 84.

The paper tube then moves along the cylindrical mandrel 62 to a pair of semi-cylindrical guides 92 which completely surround the mandrel 62. The guides 92 are secured by means of supports 94 on an adjustable plate 96. Each of the

adjustable plates 96 has a slot 98 which symmetrically diverges from the axis of the cylindrical mandrel 62. The plates 96 rest upon a base 100 which is suitably supported on table 10 by block 102. The plates 96 are adjustably mounted on the base 100 by the bolts 104 which extend through the diverging slots 98 and have suitable winged nuts clamping the plate 96 to the base 100. An additional folding finger 106 may also be suitably supported by a post 108 secured to one of the supports 94.

The paper tube then passes along the mandrel 62 to the driving and sealing mechanism which is mounted on a rectangular frame 112 having a channel-shaped cross section and suitably supported on the table 10 by support blocks 114. The frame is made in two parts in order to provide easy access to service and remove the mandrel. The lower part 116 is pivoted by hinge 118 to the upper part 120. At the opposite side of the frame a locking bolt and hand wheel 122 are pivotally secured to the lower portion of the frame 116 and are swingable into the slot in the latch plate 124 which is secured to the upper portion 120 of the frame. The driving mechanism is driven by the pulley 126 which is mounted on the shaft 128 as best shown in Figure 3. The shaft 128 is suitably journalled in a bearing 132 in the lower portion of the frame and bearings 134 and 136 located beneath the mandrel 62 on each side of the center of the mandrel. A rubber drive wheel 138 is mounted on the shaft 128 between the bearings 134 and 136. The rubber wheel 138 is secured to the shaft by being clamped between suitable hub members 140 which are secured to the shaft. A bevel gear 142 is secured to the outboard end of shaft 128 beyond bearing 136 and meshes with a bevel gear 144 on the end of shaft 146 which is suitably journalled in bearings 148 and 152 secured to the upper portion 120 of the frame. A rubber wheel 154 is secured in the same manner as wheel 138 to the shaft 146 by a hub 156. A bevel gear 158 is secured on the outboard end of shaft 146 and meshes with a bevel gear 162 on shaft 164. The shaft 164 is suitably journalled in bearings 166 and 168 and supports a driving and heating wheel 172 which is suitably secured to the shaft 164. The wheel 172 is made of metal and has an annular electric heating element 174 located adjacent to the perimeter of the wheel. The electricity is supplied to the heating element 174 by means of the wires 176 extending through a hollow portion 178 of the shaft 164. The electric current is transferred from a terminal box 182 mounted on the frame 112 by means of brushes 184 which engage a pair of commutator rings 186. A gear 188 is secured to the shaft 164 adjacent to bearing 168 and meshes with a gear 192 on shaft 194. The shaft 194 is suitably joined in bearings 196 and 198 which are supported on the upper portion 120 of the frame. Between the bearings 196 and 198 a rubber wheel 202 is mounted on the shaft by means of a suitable hub 204. It will be noted that the wheels 138 and 172 are located on the vertical axis of the mandrel 62 and that the wheels 154 and 202 are mounted on the horizontal axis of the mandrel 62. Each of these wheels has a concave surface and contracts an idler roller 206 which has a transversely convex surface to conform with the exterior surface of the mandrel 62. The rollers 206 are mounted on a bearing 208 which is supported on a pin 212 and mounted in suitable apertures in the bulkhead 214. The bulkhead 214 has cavities for the

rollers 206 and has sufficient length to extend beyond both ends of the apertures 216 in the surface of the mandrel 62 through which the rollers 206 contact their adjacent driving wheels. Thus the air pressure between the paper and the hollow mandrel will not escape out of the apertures 216. The bulkhead 214 has a central aperture 218 connecting with passage 78 to allow the passage of air through the bulkhead.

After the paper tube passes through the driving and sealing rollers in frame 112 it enters another set of driving and sealing rollers in a frame 222. A frame 222 has a second set of rollers 138, 154, 172 and 202 located and driven in the same manner as in frame 112. The upper roller 172 may be the heating roller but is preferably a rubber driving roller such as roller 154. The frame 222 has a driving shaft 128 extending thereof which has pulleys 224 and 226 secured thereto. The shafts 128 in each of these frames 112 and 222 are interconnected by a belt 228 which interconnects pulleys 224 and 126. The pulley 226 is driven by a belt 230 which extends downwardly to a suitable pulley on a driven shaft of gear box 232. The electric motor 234 suitably drives the gear box through the belt 236 which is connected to the pulley 238 on the input shaft of the gear box. The driving wheels of frame 222 engage a second set of rollers 206 mounted in a second bulkhead 216.

The forward end of the mandrel forward of the frame 222 gradually changes from a circular cross section to a square cross section having substantially the same perimeter. At this point the mandrel has a sharply tapered or reduced portion 240 which sharply reduces the size of the mandrel to the square extended portion 242 which fits in the central aperture of the bellows forming on this machine. The tapered portion 240 of the mandrel has a plurality of apertures 244 on each portion to allow air pressure to support the paper tube in this region.

The pleat forming mechanism is mounted about this reduced portion of the mandrel and is supported from an annular plate 246 supported in vertical position on a pair of legs 248 secured to a sliding plate 252. The plate 252 is slidably mounted on a table 10 and retained in position by guides 254. The forward and rear position of the folding mechanism with respect to the mandrel 62 is regulated by an adjusting mechanism best shown in Figures 1 and 3. An elongated stud is secured to the central portion of the plate 252 and extends through apertures in the bifurcated portion of anchorage 256. A nut 258 is threaded on the stud 255 and located between the bifurcated portion of the anchorage 256 so that the plate 252 may be moved forwardly or rearwardly by rotating the nut 258. The pleat folding mechanism consists of four series of pleat formers. There is a top series 260 and a bottom series 262 positioned on the vertical axis of the mandrel above and below the center. One side series 264 is located on the right side of the mandrel and the other 266 is located on the left side of the mandrel as viewed in Figure 11. Each of these series of folding plates 260, 262, 264 and 266 consists of a plurality of trapezoidally shaped formers 268 which are best shown at the top and bottom in Figure 11. As best shown in Figure 12, each of the formers 268 has an apertured pintle portion 270 at the base and a pair of ears 272 extending at right angles therefrom and having an apertured portion engaging the outside of the pintle of the adjacent former 268. Thus, as

the adjacent formers 268 are pinned together by pins 274 extending through the apertured ears and pintle portions, they form a chain which extends over sprockets 276 and 278. The sprockets 276 and 278 are secured respectively to shafts 282 and 284 which are mounted in bearings supporting apertures in the bearing supporting arms 286. These arms are located on each side of the pleat formers and extend generally rearwardly and toward the axis of the mandrel 62. The shaft 284 is supported close to the axis of mandrel 62 so that the pleat formers pass closely adjacent to the tapered portion of the mandrel to grip the paper and the shaft 282 is further removed from the mandrel so that the pleat formers travel along the mandrel to shaft 284 and gradually recede from the mandrel to completely release the pleats of the folded bellows. The arms 286 have an adjustable portion 288 which supports the bearing shaft 284. Thus the chain consisting of a series of formers 268 can be made taut by adjusting the position of support 288 for shaft 284. The adjustable portion 288 of support arms 286 is adjusted by a set screw 290 and held in position by blocking the screw 292. Each of the shafts 284 has a bevel gear 294 at each end. The bevel gears 294 mesh with each other so that all the shafts 284 are driven at the same speed. Similarly, a gear 296 is attached to each end of each of the shafts 282. The gears 296 on the ends of adjacent shafts 282 mesh with each other to drive the gear and the shafts at the same speed.

The pleat formers are driven by extending the shafts 282, 284 on the lower set of pleat formers 262. This shaft 282 extends outwardly through a bearing 298 mounted on the plate 252 by a support 302. A sprocket 304 is secured to the shaft 282 on the outboard side of bearing 298. A chain 306 running on the sprocket 304 and the output shaft of the variable speed gearbox 232 provides the power to drive the pleat formers. The shaft 284 of the lower group of pleat formers 262 is also extended through a bearing 308 mounted on support 302. On the inward side of the bearings 298 and 308 the shafts 282 and 284 are inter-connective by gearing best shown in Figure 10. This gearing consists of a spur gear 312 secured to the shaft 282 and a pinion 314 secured to the shaft 284. These gears are inter-connected to rotate in the same direction by the idler gear 316 which is mounted to mesh with both gear 312 and pinion 314 by the stub shaft 317 on adjustable arm 318.

The paper or sheet material used in this folding machine is supplied in strips or ribbon form rolled on suitable supply drums. The material is drawn by the machine from a suitable drum and enters the machine over the roller 18 and moves between the platen 22 and the guide 24. As the paper leaves the guide the nozzle 28 applies adhesive material to the underside of one edge of the sheet material and another nozzle 52 applies adhesive to the upper side at the other edge. The sheet material in flat form as shown at 322 in Figure 2 then passes on to the entrance edge 58 of the external former 60. The external former gradually tapers from the flat section at the entrance section 58 to a rounded section with a large opening at the top in the intermediate region. At this point a cylindrical internal former or mandrel is positioned centrally within the external former. This mandrel about which the tube is formed extends forwardly in the machine. The external former continues to con-

verge upon the mandrel so that at the outlet end of the external former it has a circular shape closely surrounding the cylindrical mandrel and forming the paper sheet material into a tube at 324. The fingers 28 and 106 are positioned in 5 324. The fingers 28 and 106 are positioned in contact with the edges of the sheet material to assure the uniform overlapping of the sheet material preparatory to the final sealing operation. Generally the first finger 28 presses the inner edge of the sheet material against the mandrel, while the second finger 106 presses the top edge on the inner edge. The tube then passes through a guide portion 92 which holds the tube in a proper position around the mandrel for the driving and sealing of rollers mounted in frame 112. The rubber rollers or wheels 138, 154, and 202 10 contact the outside of the paper while the inside is contacted by the idler rollers 206. The top roller or wheel 172 which contacts the paper over the conventional idler roller 206 has an electric heating element 174 to seal the adhesive or heat sealing resin to secure the joint in the tube. The tube then passes forwardly on the mandrel to a second and similar series of driving rollers. This second series of rollers is merely employed to minimize likelihood of a localized strain on the tube that might tear the tube while it is going through the machine. The tube then passes to the section of the mandrel which changes from a cylindrical cross section 20 to a square cross section 326 in Figures 2 and 12. It will be noted that the surfaces of this square end of the mandrel are in alignment with the edges of the pleat formers. The square tube then moves off the square end of the mandrel and over the tapered portion 240 of the mandrel. At this point air pressure entering through the hollow mandrel and apertures 244 maintains an outward pressure within the tube to hold it at its square form. Thus, when the top pleat former 260 and the bottom pleat former 262 engage the paper tube to form an inside crease between a pair of pleats, the air pressure maintains the pleat extending between the pleat formers. As the top and bottom pleats are moved forwardly by the top and bottom pleat formers, a right pleat former 264 and a left pleat former 266 simultaneously engage the tube and form an inward crease between a pair of side pleats. The air pressure maintains the paper extended between the pleat formers to form the outwardly extending pleat. The process is then repeated when the next top and bottom pleat formers form another pleat and the side pleat formers form another pleat so that the pleats are continuously formed as the paper tube continuously moves through the machine. It is preferred that the top and bottom pleat formers complete the formation of the top and bottom pleats before the next pair of side pleat formers engage the tube to form the next side pleats. Similarly, these side pleats are completed before the next top and bottom pleat formers engage the tube to form the next top and bottom pleats. The preceding pleat can be completed before the next pleat is started, due to the fact that the formers 268 spread apart when they pass over the small diameter sprocket 278. They should spread far enough apart so that there is no interference and the next adjacent former will not engage the paper before the prior former has completed its pleat. In one machine making a bellows about 4 inches in diameter and employing formers about 1½ inches deep, a small 15 diameter three tooth sprocket which will spread

the formers 120° apart operates successfully. As best shown in Figure 12, the shaft 282 is spaced further from the axis than the shaft 284 so that as the pleat formers move longitudinally along the mandrel they recede from the mandrel and are gradually withdrawn from between the pleats of the bellows. The bellows 328 are mounted in a central position between the pleat formers as they are withdrawn by the extension 242 of the mandrel. The machine makes a continuous alternately pleated octagonal bellows which may be cut to any desired length.

The above described bellows forming machine is a preferred embodiment of the invention. It will be apparent that numerous variations of the invention may be made within the scope of the patented claims.

We claim:

1. In a folding machine, a mandrel, means to form a continuous strip into a tube around said mandrel, said mandrel having a reduced portion at the end, means to supply compressed air between the tube and the reduced portion of the mandrel, and means to form pleats in the tube engaging the outside of the tube over said reduced portion comprising an endless belt having a plurality of pleat formers mounted radially on said belt.

2. In a folding machine, a mandrel, means to form a continuous strip into a tube around said mandrel, said mandrel having a reduced portion at the end, means to supply compressed air between the tube and the reduced portion of the mandrel, a plurality of series of pleat formers, and each series of pleat formers being mounted on an endless belt to engage said tube over said reduced portion.

3. In a folding machine, means to guide a tube along its axis, said guide means having a rectangular terminal portion and an adjacent reduced portion, means to drive said tube on said guide means, means to supply air pressure at the reduced portion of said guide to internally support said tube, means to confine said internal air pressure, an endless belt, pleat formers mounted on said belt, one end of said belt being mounted adjacent said tube so that the pleat formers engage said tube at the reduced portion of said guide, and the other end of said belt being mounted further away from the axis so that the pleat formers are automatically withdrawn from said pleats.

4. In a folding machine, means to guide a tube, means to internally support a tube, an endless belt positioned above and below said guide, an endless belt positioned on each side of said guide, formers on said belts, one end of each of said belts being positioned adjacent said guide to pleat said tube, and the other end of said belts being positioned away from said tube to withdraw said formers from said pleats.

5. In a folding machine, means to guide a tube having a reduced portion, means to internally support a tube, an endless belt positioned above and below said guide, an endless belt positioned on each side of said guide, formers on said belts, one end of said belts being positioned adjacent said guide to carry the formers into said reduced portion to pleat said tube, and the other end of said belts being positioned away from said tube to withdraw said formers from said pleats.

6. In a folding machine, means to guide a tube, means to internally support a tube, an endless belt positioned above and below said guide, an endless belt positioned on each side of said guide

formers on said belts, one end of each of said belts being positioned adjacent said guide to pleat said tube, and the other end of said belts being positioned away from said tube to withdraw said formers from said pleats, and means to drive said belts so that the pleat formers positioned above and below the guide engage the tube alternately with respect to the side pleat formers.

7. In a folding machine, a mandrel, means to form a continuous strip into a tube around said mandrel, said mandrel having a portion of rectangular section with all sides having a width substantially greater than the thickness of the continuous strip to substantially space internal opposed sides of the tube and a portion of reduced section with all transverse dimensions less than the same transverse dimension of said rectangular portion, means to supply compressed air between the tube and said reduced portion of the mandrel, means to form pleats in the tube engaging the flat sides of said rectangular portion of the outside of the tube over said reduced portion, and means to disengage said pleat forming means from said tube.

8. In a folding machine, means to guide a tube and angularly position adjacent sides of the tube, fluid pressure means to internally support a tube, a first endless belt having a series of formers positioned to engage a first side of the tube to form pleats, and a second endless belt having a series of formers positioned at a transverse angle to said first endless belt to engage a second side of the tube located at an angle to the first side to form pleats.

9. In a folding machine, a support, means having an axis mounted on said support to guide a tube for movement coaxially along its axis, means mounted on said support and engaging the tube to drive said tube coaxially in one direction on said guide means along said axis, fluid means mounted on said support and located within the tube to confine fluid under pressure within a portion of said tube, means mounted on said support and connected to said fluid means to supply fluid under pressure to said confining means to internally support said portion of said tube, means forming pleats in said tube including an endless belt rotatably mounted on said support, pleat formers mounted on said belt, one end of said belt being mounted on said support adjacent said portion of said tube and said pleat formers engaging said portion of the tube to form pleats in cooperation with said fluid means, the other end of said belt being mounted on said support further away from the axis and said pleat formers being automatically moved with the tube and withdrawn from said pleats.

10. In a folding machine, a support, guide means having an axis mounted on said support to guide a tube for movement coaxially along its axis, said guide means having a portion of rectangular section to rectangularly shape the tube and a folding station, means mounted on said support to drive said tube axially on said guide means from said portion of rectangular section to said folding station, fluid means mounted on said support within said tube at said folding station to confine fluid under pressure within the tube portion of rectangular section to support 70 said tube, means to supply fluid under pressure to said fluid means to internally support said tube portion of rectangular section, means forming pleats in said tube including a first endless belt mounted on said support and extending 75

axially adjacent said guide means, a second endless belt mounted on said support and extending axially adjacent said guide means and located at a transverse angle to said first endless belt, pleat formers mounted on said belts, one end of said belts being mounted adjacent said tube opposite said fluid means and said pleat formers engaging the air pressure supported portion of said tube to form pleats in cooperation with said fluid means, the other end of said belt being mounted further away from the axis and said pleat formers being automatically moved with the tube and withdrawn from said pleats.

11. In a folding machine, a guide having a folding station holding opposite sides of a tube in spaced relation about the tube axis at said folding station, a folding member transversely positioned adjacent one side of said guide at the folding station, mechanism moving said folding member in a unidirectional cyclic path where the member during each cycle is moved substantially perpendicularly inwardly toward said axis and remaining spaced from said axis to perform a folding operation on one side of the tube while

20 said one side remains in spaced relation to the other side of the tube and then in parallel relation to the pleat move longitudinally and outwardly to withdraw said folding members from the tube, means cooperating with said mechanism

25 to internally support said tube at the folding station, and to move the tube in one direction through the folding station to present another tube portion during each cycle of movement of said mechanism.

30 12. In a bellows folding machine, a support, guide means having a folding station and mounted on said support to guide a tube axially and hold opposite sides in spaced relation, means mounted on said support and operatively engaging

40 the tube to continuously move a sheet material tube axially along said guide means, means mounted on said support to apply internal fluid support to said tube at said folding station, and means mounted on said support and continuously moving with the sheet material tube axially along said guide means and moving transversely inwardly toward said tube and having transverse lineal portions engaging said tube to form transverse pleats in one side of said tube while said one side remains in spaced relation to the other side of the tube at said folding station.

45 13. In a folding machine, fluid support means to supply and confine internal air pressure in an axially extending portion of a tubular blank to internally support the tubular blank, means to form the internally supported portion of the blank into a tube of polygonal section having opposed sides transversely substantially spaced from each other, means to form transverse pleats

50 including a transverse pleat former having a transversely extending lineal creasing means located at said fluid support means and engaging one side of said internally supported polygonal section along a transverse line to form transverse pleats in said one side while spaced from the other side, and means to move the tubular blank over said fluid support means and to move said pleat former cooperatively to support and pleat successive portions of the tubular blank.

55 14. In a folding machine, fluid support means to supply and confine internal air pressure in an axially extending portion of a tubular blank at a folding station to internally support the tubular blank, means to form the blank into a tube of rectangular section having opposed sides substan-

11 substantially spaced from each other by said fluid support means at said folding station, transverse pleat formers having transversely extending lineal creasing means at said folding station engaging one side of said rectangular section supported by said fluid support means along a transverse line to form transverse pleats in said one side, and means to move said pleat formers and means to move the blank over said fluid support means into operative engagement with said transverse pleat formers to support and pleat successive portions of the tubular blank.

15. In a bellows folding machine, guide means having a folding station, said guide means having a portion with a polygonal section having all sides of substantial length to guide said tube of polygonal section to said folding station, means to apply internal fluid support to said tube at said folding station adjacent said polygonal section of said guide means, means to continuously move a sheet material tube axially along said guide means over said portion of polygonal section to said folding station, and means positioned adjacent and movable to engage the adjacent flat sides of the polygonal section of the tube at said folding station and forming pleats in adjacent angularly related sides of the tube.

16. In a folding machine, a mandrel having a longitudinal axis, means to form a continuous strip into a tube coaxially around said mandrel, 30 said mandrel having a reduced portion at the end, all transverse dimensions of said reduced portion being less than the corresponding transverse dimension of said mandrel adjacent said reduced portion, means to supply compressed air between the tube and the reduced portion of the mandrel, and means to form pleats in the tube re-engaging the outside of the tube over said reduced portion.

17. In a folding machine, a guide having a first 40 portion having a large polygonal section, a second portion having a tapered reducing portion and a third portion having a small polygon section extending axially of said guide, means to move a tube fitting said large portion of the guide axially along said guide from the first portion to the third portion, transverse formers having a transversely extending creasing member to fold transverse pleats in the tube at the reducing portion to reduce the internal diameter of said tube to fit the small extension, means to supply compressed air to the reducing portion to hold the tube in contact with the folding means, and said large portion and said small extension of said guide means confining said air within the portion of said tube over said reducing portion.

18. In a folding machine, a guide having an axis to guide a tube axially and hold opposite sides in spaced relation at a folding station, means to supply and confine compressed air in a tube at said folding station to hold the opposed sides of the tube in spaced relation, a plurality of folding members completely surrounding said tube at said folding station, each of said plurality

of folding members having a lineal creasing member extending transversely of the axis of said guide means to engage the tube, means to continuously move the tube on said guide past said folding station, and means to move said folding members longitudinally of and inwardly toward said axis to engage all sides of the tube with said members of said folding means to form a series of transverse pleats in each side of said tube as the tube moves past said folding station.

19. In a folding machine, a guide having a folding station to guide a tube axially through the folding station, drive means to move the tube in one direction through the folding station with the internal sides of the tube substantially spaced from each other, folding means at said folding station cooperatively engaging opposite surfaces of the same tube wall portion to form pleats including mechanism at the folding station moving in one direction in a cycle to engage, fold and withdraw from one surface of the tube, fluid means at the folding station movably supporting the opposite surface of the tube wall portion to coat with said mechanism to form pleats, and said drive means moving the tube through the folding station to place successive portions of said tube at said folding station between said mechanism and fluid means so that a series of individual pleats are formed in said tube.

20. In a folding machine, a guide having a folding station to guide a tube axially through the folding station, drive means to move the tube in one direction through the folding station with the internal sides of the tube substantially spaced from each other, folding means at said folding station cooperatively engaging opposite surfaces of the same tube wall portion to form pleats including mechanism at the folding station moving in one direction in a cycle to engage, fold and then in parallel relation to the pleat simultaneously move with the tube and withdraw from one surface of the tube, means at the folding station movably supporting the opposite surface of the tube wall portion to coat with said mechanism to form pleats, and said drive means moving the tube through the folding station to place successive portions of said tube at said folding station between said mechanism and means so that a series of individual pleats are formed in said tube.
